US0D1112184S

(12) **United States Design Patent** (10) **Patent No.:** **US D1,112,184 S**
(45) **Date of Patent:** **** Feb. 10, 2026**

(54) **COVER FOR TELEPHONE**

(71) Applicant: **AIKLO TECHNOLOGIES, S.L.**,
Barcelona (ES)

(72) Inventor: **Sergio Ehlis Pirretas**, Barcelona (ES)

(73) Assignee: **AIKLO TECHNOLOGIES, S.L.**,
Barcelona (ES)

(**) Term: **15 Years**

(21) Appl. No.: **29/899,459**

(22) Filed: **Aug. 9, 2023**

(30) **Foreign Application Priority Data**

Feb. 10, 2023 (EM) 015011102-0009

(51) **LOC (15) Cl.** **03-01**

(52) **U.S. Cl.**

USPC **D14/250**; D3/218; D14/253

(74) Attorney, Agent, or Firm — Bay State IP, LLC

(57) **CLAIM**

The ornamental design for a cover for telephone as shown and described.

DESCRIPTION

FIG. 1 is a top view showing our new design for a cover for telephone;

FIG. 2 is a side perspective view showing the new design in an alternate configuration;

FIG. 3 is a back perspective view showing the new design in an alternate configuration;

FIG. 4 is a front view thereof;

FIG. 5 is another back perspective view showing the new design in an alternate configuration;

FIG. 6 is a left side view thereof;

FIG. 7 is a back view thereof;

FIG. 8 is a bottom view thereof; and,

FIG. 9 is a right side view thereof.

The broken lines illustrate portions of the covers for telephones that form no part of the claimed design.

1 Claim, 9 Drawing Sheets
